POT STRAINER

William Marcus, Cleveland, Ohio, assignor to Merrymaid
Plastics Corporation, Cleveland, Ohio, a corporation of Ohio

Filed Nov. 3, 1960, Ser. No. 62,727

Term of patent 14 years

(Cl. D44—29)

FIG. 3

Figure 1 is a top plan view of the pot strainer showing my new design;

The essential feature of my design resides in the particularly shaped handle and mounting therefor, in combination with the strainer element as shown.

I claim:

The ornamental design for a pot strainer, as shown and described.
